CLAIM

The ornamental design for a watch as shown and described.

DESCRIPTION

FIG. 1 is a front perspective view of a watch showing our new design;

FIG. 2 is a rear perspective view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a front elevational view thereof;

FIG. 8 is a rear elevational view thereof; and,

FIG. 9 is an enlarged view of a portion of FIG. 1.

The broken lines depict portions of the watch and form no part of the claimed design. The dash-dot-dash broken lines extending along the front of the watch in FIGS. 1, 3-4 and 7 represent a boundary only and form no part of the claimed design. The other dash-dot-dash lines encircling portions of the watch in FIGS. 1 and 9 are included to show a partially enlarged view only and form no part of the claimed design.
